L. BLACKMORE

REFRIGERATOR CONTROL

Filed June 15, 1922

Inventor

Lloyd Blackmore

UNITED STATES PATENT OFFICE.

LLOYD BLACKMORE, OF HIGHLAND PARK, MICHIGAN, ASSIGNOR, BY MESNE ASSIGNMENTS, TO DELCO-LIGHT COMPANY, OF DAYTON, OHIO, A CORPORATION OF DELAWARE.

REFRIGERATOR CONTROL.

Application filed June 15, 1922. Serial No. 568,534.

This invention relates to refrigerators and more particularly to the controls therefor.

In refrigerators of all types and more especially in automatically operated refrigerators for small shops or for domestic purposes, it is desirable to maintain normally a predetermined temperature and it is often desirable to obtain temporarily a different temperature. One of the objects of the present invention is to provide a system having the above characteristic and in which the temporary phase of operation may be obtained without disrupting the control mechanism. It is common practice to construct the refrigerator with a freezing compartment and to provide said compartment with removable receptacles within which water, desserts, etc. may be frozen. It is advantageous and often desirable to modify or hasten the freezing process and one of the objects of this invention is the provision of adjusting means for accomplishing this function.

Other and further objects and advantages of the invention will appear as the description proceeds.

On the drawing, Fig. 1 is a front elevation of a refrigerator, with parts broken away; and,

Fig. 2 is a detail view, on an enlarged scale.

The adjusting device will take different forms to accommodate the different types of control mechanism but in any event the lever or handle for operating the adjusting mechanism will be located in a position convenient to the operator. The device is preferably provided with a plate or dial located on the refrigerator having suitable legends thereon indicating to what position to move the hand or lever for fast or slow freezing, as is clearly indicated on Fig. 2 of the drawing.

For simplicity of illustration and convenience in description, the refrigerating mechanism is shown more or less diagrammatically and only such parts of the same are shown as are necessary to an understanding of the construction and operation of my invention and its application to said mechanism. The device is shown as being associated with an automatically operated domestic refrigerator of the compression type in which a fluid thermostat is employed, but it is understood that the same principle may

be employed on any type of refrigerators employing this or other forms of thermostats or other equivalent control devices.

On the drawing, the reference character 10 designates a refrigerator cabinet having the refrigerating or cooling chamber 11; the food or cooling compartments 12 and 13; and the lower compartment 14 for enclosing the motor 15 and the automatic controlling mechanism 16, all of which are of the usual or well-known construction.

Since the specific construction of the controlling mechanism constitutes no part of my invention it is not thought necessary to describe all the details of said mechanism. The controlling mechanism shown is that employed in a well-known make of refrigerators now on the market and is the same as that disclosed in application S. N. 146,715 of Bechtold and Mellowes, filed February 5, 1917, now Patent No. 1,478,421, dated December 25, 1923, in which a pressure actuated mechanism, controlled by a weight 17 is employed for controlling the water valve and in which a fluid thermostat located within the refrigerator is employed to operate the electric switch for controlling the compressing motor. It is to be understood, however, that the thermostat herein described is merely used to exemplify one form of the invention and that equivalent means, which is adapted to control the operation of the refrigerating apparatus in accordance with temperature variations or requirements of the apparatus being cooled, may be utilized. As shown, a diaphragm 18 is adapted to be expanded by fluid pressure to operate the lever arm 20 on which is secured the weight 21. The forward end of the arm 20 has attached thereto the weight 22 to which is connected the link 23 which operates an electric switch located in the switch box 24.

When the fluid in the thermostat expands it elevates the lever 20 and permits the weight 22 to carry the switch operating link 23 downwardly to close the switch and when the fluid in the thermostat cools it contracts and permits the weight 21 to descend thus causing the link 23 to be elevated to open the switch.

The temperatures at which the electric switch is opened and closed depends upon the adjustment of the control mechanism. In practice, the device is properly adjusted at the factory and when once adjusted the

100

105

110

adjustment is not to be disturbed except by, or under the supervision of, an expert. It is often desirable, however, to temporarily adjust the control so that the refrigerator may be temporarily maintained at a considerably lower temperature, as when the user wishes to hasten the freezing process. In order to accomplish this temporary adjustment without the assistance of an expert, suitable mechanism arranged within convenient reach of the operator is provided whereby the control mechanism may be adjusted with facility, at the will of the operator.

In the embodiment disclosed, this mechanism comprises a resilient member such as the spring 25, the lower end of which is adapted to be connected to the outer end of the lever arm 20 by any suitable means, as the link 26, which extends through an enlarged opening 26^a in said lever arm. The link is provided at its lower end with nuts whereby the effective operation of said spring may be properly adjusted. The upper end of said spring is adapted to be connected to the outer end of an arm 27 on the shaft 28. The shaft 28 is journaled in the front wall 29 of the refrigerator and has the operating handle 30 attached to the front end thereof.

Any suitable means may be provided for retaining the handle in adjusted position. As shown, a plate or quadrant 31 having suitable legends thereon is secured to the front face of the wall 29 and may have the shaft 28 journaled therein. The plate or quadrant 31 is provided with means for holding the handle 30 in any one of a plurality of positions. As shown, the plate or quadrant is provided at the sides thereof with the stops 32 and 33 for limiting the downward movement of the handle when it is in either extreme position. The lever and arm are so arranged that when the arm is on the stop 33 the tension of the spring will hold the handle against said stop. While the handle is shown as being held in only two positions it is understood that it may be otherwise.

During the normal operation of the refrigerator the handle 30 is in the position shown in Fig. 1 in which the spring is not in tension and the rod 26 is free to slide through the opening 26^a as the lever 20 moves up and down during its normal operation.

When it is desired that the temperature of the refrigerator shall be lowered in order to hasten the freezing process, or, for any other reason it is desirable to lower the temperature of the refrigerator, the handle 30 is moved to the right in contact with the stop 33, as shown in Fig. 2, which will place the spring 25 under tension and will thus assist in supporting the weight 20. This will permit the fluid thermostat to lift the

weight 21 at lower temperatures to open and close the switch for the compressing motor and will thus result in materially lowering the temperature of the interior of the refrigerator. The temperatures at which the freezing chamber will now be maintained will depend on the adjustment of the tension of the spring 25 but in any event, water, desserts, etc. placed within the refrigerating chamber may be frozen in a much shorter period of time than is possible in the normal operation of the refrigerator.

While the device has been described as being associated with refrigerators in which the temperature within the refrigerating chamber is normally maintained at a point slightly below the freezing point of water, it is understood that it may be employed on refrigerators in which the control has been adjusted to maintain the interior thereof at any suitable temperature. In other words, by the use of my device, the temperature of a refrigerator may be materially lowered over that maintained during its normal operation.

It will be understood that various changes in the form, construction, composition and arrangement of the several parts may be resorted to without departing from the spirit and scope of my invention; hence I do not wish to limit myself strictly to the structure herein set forth, but

What I claim is:

1. Refrigerating apparatus comprising, in combination, a cabinet, a cooling unit within said cabinet, means for circulating a refrigerant medium through said unit, control means for automatically controlling said apparatus, said control means having adjustable means for regulating same for normally maintaining a predetermined temperature condition of said cooling unit, auxiliary means within the cabinet for temporarily modifying the operation of the first means to obtain temporarily a different temperature in the cooling unit, and means extending through a wall of said cabinet and associated with said auxiliary means for controlling the latter.

2. Refrigerating apparatus comprising, in combination, a cooling unit, means for circulating a refrigerant medium through said unit, control means for automatically controlling said apparatus, said control means having adjustable means for regulating same for normally maintaining a predetermined temperature condition of said cooling unit, auxiliary means for temporarily modifying the action of the first-mentioned means to obtain temporarily a different temperature in said unit, and means for rendering said auxiliary means operative, said last named means having adjustable provisions for varying the effectiveness thereof.

3. Refrigerating apparatus comprising a

cooling unit; means for circulating a refrigerant medium through said unit; control means for automatically controlling said mechanism for maintaining the temperature of said unit within predetermined limits, said means including an operating member, and a resistance means for said operating member; and means cooperating with said member for modifying the action of said control means to cause operation of the mechanism between other temperature limits, said last mentioned means comprising a resistance device connected with the operating member; and means for regulating the effect of said resistance device.

4. Refrigerating apparatus including a cabinet and mechanism for producing refrigeration therein; control means for automatically controlling said mechanism for maintaining the temperature within said cabinet within predetermined limits; and auxiliary means for modifying the action of said mechanism for changing the lower temperature limit while maintaining the upper temperature limit unchanged, said auxiliary means having provisions for rendering the same inoperative and for automatically restoring said mechanism to the normal control of said control means.

5. Refrigerating apparatus including a cabinet and mechanism inclosed within the cabinet for producing refrigeration therein, control means for automatically controlling said mechanism for maintaining the temperature within said cabinet within predetermined limits, said control means having adjustable means for regulating same, and auxiliary means for modifying the action of said mechanism whereby it will operate to maintain temperatures between other limits, said auxiliary means having provisions operable from the exterior of the cabinet, for rendering the same inoperative and for automatically restoring said mechanism to the normal control of said control means.

6. Refrigerating apparatus including a cabinet and mechanism for producing refrigeration therein; control means for automatically controlling said mechanism for maintaining the temperature within said cabinet within predetermined limits, said means including an operating member, and a resistance means for said operating member; and means cooperating with said member for modifying the action of said control means to cause operation of the mechanism between other temperature limits, said last mentioned means comprising a resistance device connected with the operating member, and means operable from the exterior of the cabinet for regulating the effect of said resistance device.

7. Refrigerating apparatus comprising, in combination, a cooling unit, means for circulating refrigerant medium through said unit, control means for automatically controlling said first means for maintaining the temperature of the unit within predetermined limits, and auxiliary means for modifying the action of said first means for changing one of the temperature limits of the unit while maintaining the other unchanged, said auxiliary means having provisions for rendering the same inoperative and for automatically restoring the first means to the normal control of said control means.

8. Refrigerating apparatus comprising, in combination, a cooling unit, means for circulating refrigerant medium through said unit, control means for automatically controlling said first means, said control means having adjustable means for regulating same for maintaining the temperature of unit within predetermined limits, and auxiliary means for modifying the action of said first means for changing one of the temperature limits of the unit while maintaining the other unchanged.

9. Refrigerating apparatus comprising in combination, a cooling unit, means for circulating refrigerant medium thru the unit, means for automatically controlling the circulating means including adjustable means for regulating the control means to maintain normally a predetermined mean temperature of the cooling unit, and means operable independently of the adjustable means for modifying the operation of the circulating means.

10. Refrigerating apparatus comprising in combination, a cooling unit, means for circulating refrigerant medium thru the unit, means for automatically controlling the circulating means including adjustable means for regulating the control means to maintain normally a predetermined mean temperature of the cooling unit, and means operable independently of the adjustable means for modifying the operation of the control means.

11. Refrigerating apparatus comprising in combination, a cooling unit, means for cyclically circulating a refrigerating medium thru said unit, means for automatically controlling the circulating cycles including adjustable means for regulating same to normally maintain a predetermined mean temperature of the cooling unit, and means operable independent of the adjustable means for modifying the operation of the circulating means.

In testimony whereof I affix my signature.
LLOYD BLACKMORE.
